UNITED STATES PATENT OFFICE.

WILLIAM E. SEXTON, OF NEW YORK, N. Y., ASSIGNOR TO JOSEPH D. SEXTON, OF NEW YORK, N. Y.

CENTERING-SUPPORT.

1,361,105.

Specification of Letters Patent. Patented Dec. 7, 1920.

Application filed March 12, 1920. Serial No. 365,143.

To all whom it may concern:

Be it known that I, WILLIAM E. SEXTON, a citizen of the Dominion of Canada, and resident of the borough of Manhattan, city, 5 county, and State of New York, have invented certain new and useful Improvements in Centering-Supports, of which the following is a specification.

My invention relates to supports for centering of the type used in the construction of monolithic floors and kindred concrete structures and has for its object the provision of a supporting means whereby the centering is efficiently supported during the 15 pouring and setting of the concrete or other coalescent material and whereby said centering may be readily removed at the proper time without injury either to itself, to the support or to the concrete structure. My 20 invention will be fully described herein-after and the features of novelty will be pointed out in the appended claims.

In the accompanying drawings, which for illustrative and descriptive purposes show 25 an example of my invention, without defining its limits, Figure 1 is a plan view partly in section of the support with the centering in place thereon; Fig. 2 is a sectional view on the line 2—2 of Fig. 1; Fig. 3 is a section 30 on the line 3—3 of Fig. 1; Fig. 4 is a section similar to Fig. 2 but showing the parts in a different position; and Figs. 5, 6 and 7 are detail views illustrating elements of my invention.

Primarily the invention is intended for 35 use in the construction of monolithic floors and has been so shown and will be so described; it will be understood however, that the invention may be found useful in connection with the construction of concrete 40 structures of other types and that such additional uses are to be recognized as being within the scope of the said invention.

As shown in the illustrated example my 45 improved support comprises suspending members 10 and 10^a, formed at one end with hooks or the like 11 and 11^a and provided respectively with longitudinally extending slots 12 and 12^a preferably closed at both 50 ends. The members 10 of each support are located opposite to each other in spaced relation and in juxtaposition to the members 10^a which extend in a common plane at approximately right angles to said members 55 10 as shown in Fig. 1. Main slides 13 are

slidably mounted upon the members 10 in surface engagement therewith and are provided with longitudinal slots 14 which register with the slots 12 of said members 10; at one end the slides 13 carry extensions 15 which project toward each other and are bolted or otherwise secured to blocks 16 or their equivalents. Similar main slides 13^a are mounted in slidable surface engagement with the members 10^a and also have longitudinal slots 14^a arranged to register with the slots 12^a of said members 10^a. The main slides 13^a each have one end also formed with an integral extension 15^a which projects beneath an extension 15 and is bolted or otherwise secured thereto, thus forming a unit consisting of the main slides 13 and 13^a with their extensions 15 and 15^a and the blocks 16 or their equivalents.

Auxiliary slides 17 and 17^a are mounted 75 in slidable surface engagement with the members 10 and 10^a respectively and likewise are provided with longitudinal slots 18 and 18^a arranged to register with the slots 12 and 12^a thereof. The auxiliary 80 slides 17 and 17^a are formed with outwardly projecting extensions 19 and 19^a respectively, as shown in Figs. 2 and 3.

In order that the main slides 13 and 13^a and the auxiliary slides 17 and 17^a may be 85 secured in adjusted positions or fixed upon the members 10 and 10^a, any suitable means may be provided. For instance, headed bolts 20 and 20^a and coöperating nuts 21 and 21^a may be used for this purpose, the 90 bolts in such case projecting through the registering slots 12, 14 and 18 and 12^a, 14^a and 18^a respectively and in coöperation with the nuts 21 and 21^a, serving to securely clamp the slides upon the suspending members 10 and 10^a.

In utilizing my improved support as in the illustrated example, the hooks 11 and 11^a each projecting into a sleeve 22 of wood or other suitable material are hooked over the lower flanges 23 of the I-beams 24 and 24^a, which extend longitudinally and transversely of the building and are incorporated therein as a part of the steel skeleton in the customary manner. In this way the 100 members 10 and 10^a, with the slides 13, 13^a and 17 and 17^a and the blocks 16 or their equivalents, are suspended from said I-beams 24 and 24^a, the illustrated example 105 showing two supports located at opposite 110

ends of a rectangle formed by the beams 24 and 24^a which arrangement, it will be understood, may be carried out throughout the area of the complete floor. Either at 5 this stage or previously, the slides 13 and 13^a and 17 and 17^a are adjusted to the positions necessary to secure the predetermined results and are fastened in place by means of the bolts 20 and 20^a and nuts 21 and 21^a. 10 It will further be understood that this arrangement is not an arbitrary one and may be changed; for instance if the rectangles referred to are too large, or for other reasons it may be desirable, additional supports 15 may be located at intermediate points of each rectangle formed by the beams 24 and 24^a.

Longitudinal centering strips 25 are carried upon the extensions 19 of the auxiliary 20 slides 17 and similar transverse centering strips 26 are carried upon the extensions 19^a of the auxiliary slides 17^a, these strips 25 and 26 being located at a distance below the I-beams 24 and 24^a respectively. Upright 25 side centering members 27 rest upon the hooks 11 of the members 10 and project downwardly between the same into engagement with the strips 25 and upwardly beyond the blocks or their equivalents 16. 30 Similar upright end centering members 28 rest upon the hooks 11^a of the members 10^a and depend between the same into contact with the transverse centering strips 26, said members 28 also projecting upwardly beyond the blocks or their equivalents 16. 35 The members 27 and 28 are properly cut to fit in their respective places and the parts are so proportioned that in practice a space of approximately two inches exists between 40 said members and the respective I-beams 24 and 24^a, the purpose of which will appear more fully hereinafter. A horizontal centering member 29 rests upon and bridges the space between the blocks or their equivalent 16 and is so dimensioned as to fit between and lie flush with the upright members 27 and 28.

With this arrangement the strips 25 and 26 and the members 27, 28 and 29 define and 50 provide molding surfaces whereby the concrete is molded in the form of an arch which is duplicated throughout the area of the floor.

The support further comprises clamping 55 members 30 having one end formed as hooks 31 which hook over the upper flange 23^a of the outside beams 24^b, said members 30 lying in surface engagement with and projecting beyond said beams 24^b as shown in 60 Fig. 4. The clamping members 30 are provided with a plurality of holes 32 for adjustably accommodating the screw-threaded ends of suspending members 33, which are connected with said members 30 by means 65 of nuts 34 and depend therefrom as shown

in Fig. 4. The lower ends of the suspending members 33 are formed with transverse continuations 35 arranged to support centering strips 36 similar to the strips 25 and 26; upright centering members 37 are located upon the strips 36 and in coöperation therewith form molding troughs adjacent to the outside beams 24^b as shown in Fig. 4.

After the supports have been set up in the member required to take care of the 75 particular floor in question and the centering has been properly positioned thereon, the concrete is applied or poured in the customary manner, and in sufficient quantity to cover the centering members 29 and to fill 80 the channels between adjacent side centering members 27 and end centering members 28, the bottoms of which channels are defined by the centering strips 25 and 26. Because of the spaces existing between these 85 side and end centering members and the respective I-beams the concrete passes freely around said I-beams so as to inclose the same as shown in Fig. 4. The concrete is also filled in the troughs formed by the centering strips 36 and centering members 37 adjacent to the outside beams 24^b in the manner indicated in Fig. 4.

After the concrete has become properly set the centering is removed in the following manner, the sequence of operation set forth being capable of variation in accordance with circumstances and personal desires. The bolts 20 and 20^a and nuts 21 and 21^a are loosened to release the main slides 13 and 13^a and the auxiliary slides 17 and 17^a which as a result slide downwardly upon the members 10 and 10^a thus lowering the centering strips 25 and 26 and the horizontal centering member 29 to a position 100 below the concrete work and completely free therefrom, as shown in Fig. 4, the side centering members 27 and end centering members 28 remaining in position upon the hooks 11 and 11^a. The centering member 29 and the strips 24 and 25 may now be dismantled and readily removed from the supports without injury either to the centering, the support or to the concrete. After this stage 105 has been reached the bolts 20 may be completely removed to disconnect the main slides 13 from the members 10, thus making it possible to remove the units consisting of the main slides 13 and 13^a, the members 10^a and the auxiliary slides 17^a; because of the presence 110 of the sleeves 22, which remain embedded in the concrete, the hooks 11^a of the members 10^a, may be easily withdrawn without hindrance by said concrete, thus releasing the end centering members 28 which may be 115 removed at this stage or later. It will be understood that the removal of the bolts 20 releases also the auxiliary slides 17 from the members 10, which slides 17 may thus 120 also be removed, thus leaving only the mem- 125 bers 27 and 28.

bers 10 depending from the beams 24. These members 10 may be easily removed by withdrawing the hooks 11 from the sleeves 22 whereby the side centering members 27 are 5 released and may now be also removed so that at this stage the supports with the centering have been completely removed from the concrete and are ready for repeated use. The members 30 and 33 and the centering 10 strips 36 and centering members 37 may be similarly removed by disconnecting the nuts 34 and detaching the members 33 from the members 30 as will be apparent. Should any of the centering, because of adhesion to the 15 concrete, fail to follow the slides as the latter are lowered in the manner described, such centering may easily be loosened and removed after the supports have been removed.

20 The supports are simple in construction and operation and are easily and quickly set up and readily taken down without injury to the centering which as a result may be used over and over again. The expense 25 of providing new centering for each job is thus avoided and the delay and inconvenience incidental to the fitting of such new centering is done away with; the result is an increase in economy and efficiency and a 30 very considerable saving of valuable material.

Various changes in the specific forms shown and described may be made within the scope of the claims without departing 35 from the spirit of my invention.

I claim:

1. A centering support comprising suspending members arranged in opposite pairs, the members in each pair extending 40 at approximately right angles to each other, hooks at the upper ends of said members whereby the latter are suspended, main slides mounted on said members to slide lengthwise thereof, auxiliary slides mounted 45 on said members to slide lengthwise thereof, centering members carried by said slides to define molding surfaces, said centering members being movable with said slides to

an inoperative position to permit dismantling and means whereby said slides are 50 fixed against movement upon said members.

2. A centering support comprising a plurality of suspending members arranged in coöoperating groups, a device at one end of each suspending member whereby the same 55 may be removably suspended, slides in surface engagement with opposite surfaces of a given suspending member and independently slidable lengthwise thereof from operative to inoperative positions and vice 60 versa, means on said slides for supporting centering members in predetermined relation and locking devices whereby said slides are secured against movement upon said suspending members. 65

3. A centering support comprising suspending members arranged in coöperative relation, hooks at the upper ends of said members whereby the latter are suspended, main slides mounted on said members to 70 slide lengthwise thereof, auxiliary slides mounted on said members to slide lengthwise thereof, means on said slides constituting supports for centering and means whereby said slides are fixed against movement 75 upon said members.

4. A centering support comprising suspending members arranged in opposite pairs the members in each pair extending at approximately right angles to each other, 80 slides in surface engagement with the inner faces of said members and connected to move in unison lengthwise thereof, slides in surface engagement with the outer faces of said members and movable independently 85 lengthwise thereof and means for securing said slides against movement relatively to said members.

In testimony whereof I have hereunto set my hand.

WILLIAM E. ^{his} X SEXTON.
